UNITED STATES PATENT OFFICE

WILLIAM J. DE WITT, OF AUBURN, NEW YORK, ASSIGNOR TO SHOE FORM CO., INC., OF AUBURN, NEW YORK, A CORPORATION OF NEW YORK

SHOE FORM

Application filed December 24, 1930. Serial No. 504,542.

This invention relates to an improvement in shoe forms, more particularly in shoe forms of the type which comprises a toe form and a thrust bar, or back part stay. The toe form is preferably made of celluloid or other resilient thin wall material, and is adapted to be inserted into the toe of the shoe. The thrust bar is flexible and after the toe form has been inserted into the toe of the shoe, the thrust bar is bent so that its outer end rests against the heel counter, thus exerting a resilient pressure against the toe form, and causing it to keep the toe of the shoe plumped out or free from wrinkles. Shoe forms of this general type are disclosed, for example, in my Patent No. 1,646,016, dated October 18, 1927.

One object of the present invention is to provide a shoe form in which the thrust bar has a yieldable connection with the toe form and may be adjustable as to length to adapt the shoe form for use in shoes of different sizes, thus obviating the necessity of providing shoe forms having thrust bars of different lengths dependent upon the size of the shoes with which they are to be employed.

Other objects of the invention reside in the details of construction of the connection between the thrust bar, and the toe form, in the means by which the length of the thrust bar may be adjusted, and in other features, as will appear from a consideration of the following specification taken in connection with the drawing which forms a part thereof, and in which:

Fig. 1 is a side elevation partly in section illustrating one embodiment of this invention, the form being shown in the position it will assume when inserted within a shoe;

Fig. 2 is a bottom plan view of the toe form, and a portion of the thrust bar of the shoe form shown in Fig. 1, certain parts being in section for the purpose of clarity;

Fig. 3 is an enlarged sectional view illustrating the connection between the toe form and the thrust bar; and

Fig. 4 is a bottom plan view similar to Fig. 2 illustrating another embodiment of the invention.

The shoe form herein set forth comprises a toe form 10 and a thrust bar 11. The toe form 10 is preferably of celluloid or other resilient material, having side walls which terminate in flanges 15 and 16. In the embodiment of Fig. 1, these flanges are connected by a cross brace or strip 17 of celluloid or other suitable material, the brace being secured to the flanges in any suitable manner, as for example that disclosed in my Patent No. 1,632,955, dated June 21, 1927. The brace, instead of being fixed to the flanges, may be pivotally connected thereto, as shown in Fig. 4 and illustrated in Fig. 2 of my Patent No. 1,717,839, dated June 18, 1929, so that the pivotal movement of the brace designated as 17^a will cause the walls of the toe form to expand or contract.

The thrust bar 11 preferably comprises a tube 20 of celluloid or other suitable material and a rod 21 of metal, the rod being introduced in the forward end of the tube, as shown in Figs. 2 and 4, and being provided with suitably formed threads with which to engage correspondingly formed threads in the inner wall of the tube. The outer end of the thrust bar is preferably curved to form a loop 22, which bears against the counter of the shoe here illustrated by the dotted line 23.

The thrust bar is connected to the brace 17 or 17^a by means of a sleeve 24 and bracket 25. The sleeve 24 may be of metal or other suitable material, and is internally threaded to engage with threads on the outer surface of the rod 21. At the ends of the sleeve 24 are mounted disks 26, 27 preferably concave, as illustrated particularly in Fig. 3. These disks are secured to the sleeve 24 in any suitable manner, as by peening over the ends of the sleeve at 28. Slidably movable upon the sleeve 24 is a concave disk 29 yieldably held separate from the disk 27 by a spring 30 surrounding the sleeve. The bracket 25 may be angular in cross section, comprising a base 31 and an upright 32 having a hole 33 therein. The bracket is attached to the cross brace by a rivet, or other suitable means 35 passing through the base 31. The base is preferably not clamped tightly

against the brace 17, but is spaced therefrom sufficiently so that the bracket may have a pivotal movement about the rivet 35, as an axis. The sleeve is passed through the hole 33 in the upright 32 which is preferably between the disks 26 and 29, as shown in Fig. 3. The spring 30 thus acts not only to separate the disks 27 and 29, but also acts to clamp the upright 32 between the disks 26 and 29. It will, of course, be understood that the sleeve and bracket are assembled before the disk 26 is secured to the end of the sleeve.

From the above description, it will be apparent that when the shoe form is inserted in the shoe and takes the position indicated in Fig. 1 of the drawing, the natural resiliency of the tube 20 will force the rod 21 to advance against the tension of the spring 30, which spring will yield, as indicated in Fig. 1, only to the extent necessary when the shoe form is entirely within the shoe. When a toe form having, in the place of the fixed brace 17, the pivotally mounted brace 17^a is assembled with the thrust bar it will be understood that the thrust bar not only causes the sleeve 24 to advance through the hole 33, but also causes the cross brace 17^a to swing on its pivot and thereby expand the side walls of the toe form.

The threaded connection of the rod 21 to the tube 20 and the sleeve permits a wide range of adjustment so that the shoe form can be adapted for use in shoes of any size and the top of the curve of the thrust bar 11 set at any desired height so that it may be lower than the upper edges of the side walls of the shoe or appear above them.

While two embodiments of this invention have been shown and described, it will be understood that we are not limited thereto, since other embodiments might be made without departing from the spirit and scope of the invention as set forth in the following claims.

I claim:

1. A shoe form comprising a one-piece toe form and a thrust bar, said toe form being hollow and having a cross brace connecting the walls thereof, and means yieldable longitudinally of the thrust bar for connecting said thrust bar to said cross brace.

2. A shoe form comprising a one-piece toe form and a thrust bar, said toe form being hollow and having a cross brace connecting the walls thereof, a bracket mounted upon said cross brace, and means yieldable longitudinally of the thrust bar for connecting said thrust bar to said bracket.

3. A shoe form comprising a toe form and a thrust bar, said toe form being hollow and having a cross brace connecting the walls thereof, a bracket mounted upon said cross brace, and a sleeve on said thrust bar, said

bracket and sleeve coacting to connect said thrust bar to said toe form.

4. A shoe form comprising a toe form and a thrust bar, said toe form being hollow and having a cross brace connecting the walls thereof, a bracket mounted upon said cross brace and having a hole therein, and a sleeve on said thrust bar and passed through the hole in the bracket, whereby the thrust bar is connected to said toe form. 70 75

5. A shoe form comprising a toe form and a thrust bar, said toe form being hollow and having a cross brace connecting the walls thereof, a bracket mounted upon said cross brace and having a hole therein, a sleeve on said thrust bar passed through the hole in the bracket, a movable disk on said sleeve, and a spring yieldably holding said disk in contact with the bracket. 80

6. A shoe form comprising a one-piece toe form and a thrust bar, said toe form being hollow and having a cross brace connecting the walls thereof, coacting elements on the brace and thrust bar respectively to connect the bar to the shoe form, the element on the bar being adjustable thereto. 85 90

7. In a shoe form comprising a toe form and a thrust bar, the thrust bar including a tube of resilient material, and a rod in threaded engagement with the tube and longitudinally adjustable relative thereto. 95

8. In a shoe form comprising a toe form and a thrust bar, the thrust bar including a rod, and a sleeve carried by the rod and longitudinally adjustable relative thereto, and the toe form including a bracket with which the sleeve is connected. 100

Signed by me at Auburn, New York, this 22nd day of December, 1930.
